UNITED STATES PATENT OFFICE.

FRANK E. CASE, OF CANTON, OHIO, ASSIGNOR TO THE HARVARD COMPANY, OF CANTON, OHIO, A CORPORATION OF OHIO.

FOOT REST.

Application filed August 30, 1922. Serial No. 585,312.

To all whom it may concern:

Be it known that I, FRANK E. CASE, a citizen of the United States, residing at Canton, in the county of Stark and State of Ohio, 5 have invented certain new and useful Improvements in Foot Rests, of which the following is a specification.

The invention relates to foot rests for dental chairs and the like, comprising a 10 normally horizontal main section, and a forward extension section hinged to the main section so as to be swung into the same plane therewith or to be rotated upward at an inclination thereto; and the object of 15 the improvement is to provide means for readily securing and sustaining the extended section in upwardly inclined position, and for readily releasing the same for dropping the extension downward into alignment with 20 the main section.

The invention is illustrated in the accompanying drawings, forming part hereof, in which—

Figure 1 is a perspective view of a dental 25 chair showing the improved foot rest;

Fig. 2, a fragmentary side elevation showing the main and extension sections in horizontal alignment;

Fig. 3, a front elevation showing the extension section swung upward into inclined position, and showing the improved locking bar in locking position, with one bearing bracket in section;

Fig. 4, a fragmentary plan showing the 35 main and extension sections in horizontal alignment;

Fig. 5, a longitudinal section of the same, on line 5—5, Fig. 4;

Fig. 6, a similar section of the same, showing 40 the tension section swung upward into inclined position, and a second extension section folded backward upon the first section;

Fig. 7, a fragmentary perspective view of 45 one side bearing bracket; and

Fig. 8, a fragmentary perspective view of the locking bar and lever.

Similar numerals refer to similar parts throughout the drawings.

The foot rest may include a main section 8, 50 a forward extension section 10, and a second extension section 11; and the main section may include side bars 12 and 12' connected together by plates 13 secured to ears 14 on 55 the bar as by means of rivets 15. Likewise

the side bars 16 and 16' of the extension section 10 may be connected together by plates 17 secured to ears 18 on the bar, as by rivets 19. The forward ends of the main side bars 12 and 12', terminate in bearing 60 brackets 20 and 20', and the rear end of each extension side bar 16 and 16' is provided with a swinging bracket 21.

A bearing socket 22 is provided in the inner side of the bearing bracket 20 and a bearing aperture 22' is provided in the bearing bracket 20' for receiving the ends of a pivot rod 23 extending through bearing apertures 24 in the swinging brackets 21. The pivot rod may be held in place by a coiled 65 compression spring 25 located between one swinging bracket 21 and a collar 26 on the rod held by a cotter pin 27, as shown in Fig. 3 of the drawings.

Each bearing bracket is provided on its 75 inner side with a lug 28 extending downward and thence forward to form a finger 28' on its lower end; and each bearing bracket is provided with a depending arm 29 so positioned that its end will abut the 80 finger 28' when the extension arms are in horizontal alignment with the main arms, as shown in Fig. 5; in which position there is an interval between the body of the lug 28 and the body of the arm 29. Another finger 85 28'' may also be provided on the inner side of one or both bearing brackets, at spaced intervals in front of the fingers 28', to serve as stops for the ends of the depending arms 29 when the side bars of the 90 extension section are swung upward into inclined position, as shown in Fig. 6.

Each bearing bracket is also provided with a segmental socket 30, located below the bearings for the pivot rod 23, which sockets 95 form bearings for the ends of a locking bar 31 operating between the lugs 28 on the bearing brackets and the arms 29 of the swinging brackets. The locking bar 31 has a substantial width as compared with its 100 thickness, and is preferably formed with flat sides and rounded edges. The bar is provided with an operating handle 32, which may be secured as by screws 33 at one end of the bar, just inside the swinging bracket, whence it may curve downward and outward to be engaged by the foot or the hand 105 of an operator.

The width of the locking bar normally stands in upright position, with its thick- 110

ness between the depending lugs 28 and the depending arms 29, when the extension section is in horizontal alignment with the main section of the foot rest, as shown in Fig. 5; in which position the operating handle extends rearward under the main section, as shown in Fig. 2.

When it is desired to swing the extension section upward into inclined position, pressure is applied to the operating handle 32, as by the foot of the operator, which turns the bar in its socket bearings, so that its lower edge pushes the depending arms 29 forward and swings the extension upward, by a sliding of the lower edge at the ends of the bar along the bottoms of the segmental sockets 30.

In the turning of the bar its upper edge moves downward by a sliding of the same at the ends against the lugs 28 and along the rear sides of the sockets 30, until the width of the bar is interposed between the lugs and the depending arms so as to lock the extension in upwardly inclined position, as shown in Fig. 6; in which position of the locking bar the operating handle hangs downward, as shown by full lines in Fig. 3 and by broken lines in Fig. 2.

When it is desired to drop the extension section to horizontal position, it is only necessary to swing the operating handle rearward and upward which is readily done by the foot, to the position shown in full lines in Fig. 2, which turns the locking bar and moves its rear edge upward and its forward edge rearward into normal position and permits the extension section to drop downward into horizontal position, as shown in Fig. 5.

I claim:—

1. A foot rest, including a main section having a bearing bracket at each side of its forward end, an extension section having a bracket at each side of its rear end pivotally connected with the bearing brackets,

there being a socket in each of one pair of brackets spaced from the pivotal connection and an arm depending from one of the other brackets, a flat locking bar having ends bearing in the sockets and movable therein to interpose either its thickness or its width between the rear wall of the socket and the rear edge of the arm, and a finger on one socket bearing bracket to stop the arm when the extension section is aligned with the main section. 45

2. A foot rest, including a main section having a bearing bracket at each side of its forward end, an extension section having a bracket at each side of its rear end pivotally connected with the bearing brackets, there being a socket in each of one pair of brackets spaced from the pivotal connection and an arm depending from one of the other brackets, a flat locking bar having ends bearing in the sockets and movable therein to interpose either its thickness or its width between the rear wall of the socket and the rear edge of the arm, and a finger on one socket bearing bracket to stop the arm when the extension section is aligned with the main section. 50

3. A foot rest, including a main section having a bearing bracket at each side of its forward end, an extension section having a bracket at each side of its rear end pivotally connected with the bearing brackets, there being a socket in each of one pair of brackets spaced from the pivotal connection and an arm depending from one of the other brackets, a flat locking bar having ends bearing in the sockets and movable therein to interpose either its thickness or its width between the rear wall of the socket and the rear edge of the arm, and a handle on the bar for moving it from one position to another. 55 60 65 70 75 80 85
